UNITED STATES PATENT OFFICE.

JOSEPH H. CUTLER, OF MEDWAY, MASSACHUSETTS.

CHAFE-IRON FOR VEHICLES.

SPECIFICATION forming part of Letters Patent No. 653,217, dated July 10, 1900.

Application filed October 17, 1899. Renewed May 18, 1900. Serial No. 17,172. (No model.)

To all whom it may concern:

Be it known that I, JOSEPH H. CUTLER, a citizen of the United States, residing at West Medway, in the county of Norfolk and State 5 of Massachusetts, have invented certain new and useful Improvements in Chafe-Irons for Vehicles, of which the following is a specification.

My invention relates to chafe-irons for vehicles, the object being to provide a device of this character which will combine simplicity and economy of construction with effectiveness and durability in use.

The invention comprises a supporting and 15 attaching plate, an antifriction-roller, and novel means for supporting the roller in operative relation to the attaching-plate.

The construction and novel features of the invention will be fully described hereinafter 20 and defined in the appended claim, in connection with the accompanying drawings, which form a part of this specification, and in which—

Figure 1 is a top plan view of a chafe-iron 25 embodying the invention. Fig. 2 is an end elevation of the same. Fig. 3 is a plan view of the attaching-plate detached; and Fig. 4 illustrates the roller and its supporting and securing devices detached, but arranged with 30 respect to their relation when assembled.

The reference-numeral 1 designates the attaching-plate, formed with openings 2 to facilitate its attachment to the side of a vehicle-body and having parallel projecting 35 ears 3 and 4, which are bored to receive the journals of the antifriction-roller 5. The ear 3 of the plate is formed with a bearing 6, the outer end 7 of which is of conical form to correspond to a conical journal 8, projecting 40 from the adjacent end of the roller 5. The ear 4 of the plate is formed with a through-opening 9, the outer end 10 of which is internally screw-threaded to receive a screw-plug 11. The end of the roller 5 adjacent to 45 the ear 4 is provided with a conical seat 12

to receive a pin 13, the inner end 14 of which is of conical form.

To support and secure the roller in position between the ears of the plate 1, I employ at one end of the roller a coil-spring 15, which 50 rests within the bearing 6, a concavo-convex disk 16, preferably made of steel, and a cup-shaped leather washer 17. As shown by the dotted lines in Fig. 1, the steel disk 16 bears against the spring and the cup 17 bears against 55 the disk and receives the conical end of the journal 8. At the opposite end of the plate the roller is secured by the pin 13, which is held in place by the screw-plug 11. Between the inner conical end of the bearing 12 and 60 the end 14 of the pin 13 are arranged a coil-spring 18, a disk 19, of steel, and a cup-shaped leather washer 20, similar to the parts 15, 16, and 17 at the opposite end of the roller.

The construction above described permits 65 both the openings 6 and 12 to be drilled by a single drill.

The roller is adapted to revolve freely and noiselessly, the yielding washer-cups and springs contributing to this result. 70

I claim—

The combination with an attaching-plate formed with parallel ears having aligned openings; of a roller formed at one end with a conical journal, and at its opposite end 75 with a conical bearing; a coil-spring, a disk and a washer between the conical journal and the wall of its bearing; a conical pin extending through one of the ears of the plate and projecting into the conical bearing of the 80 roller; a screw-plug for securing said pin; and a coil-spring, disk and cup-shaped washer between the conical pin and the conical wall of the roller-opening.

In testimony whereof I affix my signature 85 in presence of two witnesses.

JOSEPH H. CUTLER.
